[57] CLAIM

The ornamental design for a full back tower beverage dispenser, as shown and described.

DESCRIPTION

FIG. 1 is a top front right side perspective view of a full back tower beverage dispenser showing our new design;

FIG. 2 is a left side elevational view thereof; and

FIG. 3 is a right side elevational view thereof;

FIG. 4 is a front elevational view thereof;

FIG. 5 is a rear elevational view thereof;

FIG. 6 is a top plan view thereof; and

FIG. 7 is a bottom plan view thereof.

FIG. 8 is top front right side perspective view of a first modified form of our new design;

FIG. 9 is a left side elevational view thereof;

FIG. 10 is a right side elevational view thereof;

FIG. 11 is a front elevational view thereof;

FIG. 12 is a rear elevational view thereof;

FIG. 13 is a top plan view thereof; and

FIG. 14 is bottom plan view thereof.

FIG. 15 is a top front right side perspective view of a second modified form of our new design;

FIG. 16 is a left side elevational view thereof;

FIG. 17 is a right side elevational view thereof;

FIG. 18 is a front elevational view thereof;

FIG. 19 is a rear elevational view thereof;

FIG. 20 is a top plan view thereof; and

FIG. 21 is a bottom plan view thereof.
